UNITED STATES PATENT OFFICE.

SILAS R. VANNAMAN, OF CHICAGO, ILLINOIS, ASSIGNOR TO AMERICAN 3-WAY PRISM COMPANY, OF LAPORTE, INDIANA, A CORPORATION OF PENNSYLVANIA.

ART OF ROLLING HOLLOW-HEADED METAL BARS.

1,140,087.

Specification of Letters Patent.

Patented May 18, 1915.

Application filed April 15, 1914. Serial No. 831,917.

To all whom it may concern:

Be it known that I, SILAS R. VANNAMAN, a citizen of the United States, residing at Chicago, in the county of Cook and State of Illinois, have invented certain new and useful Improvements in the Art of Rolling Hollow-Headed Metal Bars, of which the following is a specification.

My invention relates to the art of making metallic muntins or sash-bars and the like.

In the manufacture of sky lights, prismatic-reflector windows, and the like, metallic muntins or double-channel bars are commonly employed for receiving and connecting contiguous small panes of glass, and one advantageous form of such muntin construction consists of a metallic strip formed, in cross section somewhat like a dumb-bell, to provide a central bar flanked by two hollow heads, said heads substantially at right angles to said bar and extending on both sides of the plane of said bar to make a double channel, having its parallel heads convexly curved at their outer surfaces. The bar portion of such muntin strip is usually, wholly or in part, of double thickness, one thickness of the bar being the undivided central portion of the strip and the other thickness of the bar being composed of the marginal edge portions of the strip, abutting edge to edge either in substantially meeting relation or more or less separated.

Modifications of such particular muntin construction are also employed, but the muntin strip formation above described suffices to indicate a class of metallic muntin structure to the manufacture of which my invention is particularly applicable.

Heretofore it has been commercially the universal practice, so far as I am aware, to manufacture such products wholly or in part by drawing, and such prior practice has many disadvantages from a manufacturing viewpoint. For instance, the bar is commonly made of zinc, and the drawing operation entails considerable loss of stock. Zinc sheets cut into strips of appropriate width are commonly employed as the stock from which to make the structure, but there is material wastage for several reasons. The border strips cut from the zinc plates are in

practice, nearly always "checked", or weakened by fine cracks, so that they will not stand the strain of drawing and have to be discarded. Also, each strip has to have its end folded into suitable form to receive the gripper of the drawing machine and several inches of stock-strip are necessarily wasted. Also in practice the grippers of the drawing machine often break the leading end of the stock, entailing loss of material as well as waste of time. Furthermore, the operation of such a drawing machine usually requires the attendance of two operators, one to feed the strips, the other to operate the drawing gripper. Also a disadvantage is that the strain of the drawing operation inherently requires the use of a relatively stout or thick stock, with attendant high cost and the disadvantage of increased weight in the completed article. Also in practice, the drawing dies are subject to wear, which results, during a long run, in a material change in the thickness of portions of the drawn article, and some variation in the length of the drawn bar produced from a given length of original strip-stock. By the use of my invention all of these disadvantages are overcome. In the practice of my invention I roll such strips without any drawing action whatever, and, as far as I am aware, I am the first successfully to accomplish the rolling of such bar.

By the practice of my invention I am able to produce muntin strips of the character described from lighter zinc stock than heretofore; to employ border strips cut from a plate as effectively as intermediate strips, without breakage or defective results; to decrease the cost of production very materially; to insure uniformity in the product; to enable a single operator adequately to serve the apparatus; to increase the output as to rate of production, to make all strips uniform in length and of the full length of the stock; and to avoid, substantially, all disadvantageous heating or wear of parts such as would cause variation in the product in even a very long continuous run.

In the practice of my invention I employ a machine substantially as hereinafter described, operating by the method disclosed.

In the drawing Figure 1 is a side elevation of a machine for rolling munin strips of the character described. Figs. 2, 3, 4, 5, 6 and 7 are respectively transverse sections on lines 2—2 to 7—7 of Fig. 1; Fig. 8 is a longitudinal horizontal section above the lower rolls, with the upper rolls and gearing removed; Figs. 9, 10 and 11 are perspective details showing different portions of a former-core associated with the rolls and with leading-guides. Fig. 12 is a detail of a roll adjusting eccentric; Fig. 13 is a sectional detail through leading-guide 53. Fig. 14 is a broken perspective detail of a strip taken from the machine in partially completed condition, showing the several steps in the formation of the completed article.

In the machine, the roll-couples 22—22', 23—23', etc., to 27—27' are mounted on a frame plate 28 to rotate in unison with their coacting surfaces all traveling in the same direction, under power applied to one of the roll shafts, preferably an elongated shaft 29' of roll 27'. The gearing may be varied but as here shown each roll pair is provided with a gear couple 30—30', and motion is communicated from couple to couple by idler pinions 31 connecting, in train, the several gear members 30. Each roll member, fixed to its appropriate gear member, is mounted for rotation on a short shaft 32 or 32', the last roll 27' having a special shaft 29' which is extended to receive any suitable power transmitting clutch, conventionally illustrated in Fig. 7 as 33. For adjustment of the two members of each roll couple with respect to each other, to vary the pressure between the roll members, the shaft 32 for each upper roll member preferably has its roll-bearing portion 35 (Fig. 12) eccentric to the supported bearing portion 36 which takes into the frame plate 28, so that by rotary adjustment of the shaft 32 in its frame bearing, the upper roll member may be slightly moved with respect to the lower member.

The flat metallic stock-strip 40, (Fig. 14) is fed to the rolls in predetermined position from a guide table 50 having guiding side flanges 51, and in its progress through the machine, the strip is methodically acted on by successive roll couples so that first it is symmetrically bent (in cross section) to provide a short, central bar portion, flanked by half-heads defining one channel of the completed article; then the wing or border along one edge of the strip is reentrantly rolled, preferably around a forming-core, to complete the head on one side and lay one border of the strip flat upon the central bar portion of the strip; and then the other wing portion, similarly to the first, is reentrantly rolled into the second head and its extreme border portion is laid flat on the bar part of the strip. By using a metal strip of the proper width the two extreme

border portions may be laid upon the central bar portion jointly to constitute the second thickness of said bar, and may be brought into substantial butt-contact along their edges; the successive bending of the two wings enabling them to be brought to their final positions without interference.

Because of the somewhat granular character of zinc, and its comparative low tenacity, I prefer to make each rolling operation rather mild in the change of form imparted thereby to the strip-stock, and to this end, among others, I have sub-divided each of the three steps of the operation above stated into at least two operations, and effect also a finishing operation, as may best be seen by reference to Figs. 2 to 7. The first two roll couples substantially form the lower half of the completed strip, bending it to provide the central bar forming the bottom of the channel, and two half heads flanking the bar; then the two wings are bent in jointly, to almost meeting position as part of both the second and third steps; and then the two wings are successively rolled down, reentrantly, to complete the second and third steps, after which a finishing pressure is applied to give final sharpness of definition to the munin bar. Of the first roll couple 22—22', the lower roll 22 provides a central bar-forming rib 22^a, preferably having its edges slightly rounded, and flanked by grooves 22^b beyond which are wing-deflecting flanges 22^c, preferably widely flared outwardly; and the complementary roll 22 has a central groove 22^d flanked by projecting ribs 22^e coöperating with the complementary parts of the lower roll, as illustrated in Fig. 2. At this first stage a metal strip is formed as at 42 to approximately the lower half of its ultimate section, but preferably without particular sharpness of definition of its angles, so as to avoid possibility of tearing, crystallizing or thinning too much, the metal. I find it to be preferable in practice to give the wing-shaping flanges 22^c a convex curvature, as thereby the wings of the strip are prevented from "ruffing" or wrinkling. The strip, formed to the cross section indicated at 42, passes to a leading-guide 53 which extends substantially from the periphery of the lower roll 22' to the contiguous roll 23' of the next couple so as to guide the strip substantially in the plane of tangency to the tops of the rolls, in a straight material-path that leads directly through the machine. Such guide 53 is preferably pivotally mounted on a pin 54 for slight lost motion of its receiving end, (which is slightly beveled down below the plane of travel) in a downward direction, until stopped by contact with the roll 22', its leading end being shaped for coöperation with the adjacent roll 23', normally to rest lightly on the periphery thereof under the

influence of gravity. The top surface of the guide is shaped to provide a longitudinal ridge 55 flanked by grooves 55' guidingly to coöperate with the channel and beads of the 5 partially-formed stock strip. The second roll couple 23—23' furthers the strip-formation, substantially to complete the first step of forming the lower half section of the article, by sharpening the definition of the 10 bends of the channel and said head-halves, and deflecting the wings inwardly somewhat to produce the cross-section 43. To this end the rib 23^a, grooves 23^b, of the lower roll and co-operating portions 23^c and 23^d of the upper 15 rolls are more sharply angled than in the first roll couple, and the wing-forming flanges 23^e are shaped more nearly vertical and coöperate with convexed guiding surfaces 23^f of the upper roll to produce the substantially complete 20 lower-channel formation shown in Fig. 3.

The succeeding lower rolls of the series are nearly identical with roll 23^a in their central-rib and flanking-groove formation, 25 and leading guides 56, 57, 58, and 59, that substantially correspond in construction with the guide 53, are provided in the spaces between the several rolls so that the strip is guided throughout the machine by coaction 30 of the channel first formed therein with the co-acting surfaces of the leading guides and several lower rolls. The operator has merely to feed the strip to the first roll-couple. Its progress thereafter is automatically effected 35 and it travels straight through the machine. From the second roll pair forward the rolling action is preferably aided by an interior forming core acting on the inner surface of the strip and coöperating with the successive 40 rolls and leading guides. The forming core 60, illustrated in the drawings, is carried by a stud 61 (Fig. 9) arranged between the second and third roll pairs above the work passage, said stud having a nose 62, carrying the core 60, so that the wings of the strip 45 may have free passage on both sides thereof. The forming core 60 comprises two elongated fingers or rails 60^a conforming to the interior curvatures to be imparted to the strip heads and extending longitudinally from the point of support on the stud 61, through the material-path provided by the 50 grooves of the roll pairs and of the leading guides to, preferably, substantially the acting surfaces of the terminal or finishing rolls. At its supported end the forming core 55 preferably has its rails united by a horizontal top strip or bridge 60^b, made integral therewith and extending forward to the operating 60 surface of the roll 25', the leading guide 56, subjacent to the core being preferably made narrow, to lie only within the groove between the core-rails. The partially formed strip of the cross section 43, rides from rolls 23—23' to the next roll couple on

the leading guide 56, with its wing portions straddling the rails 60^a. The guide stud 61 carries a block 65 having a properly shaped mouth 66, that steadies the wings, preferably deflecting them farther inward slightly 70 or preventing them from spreading, and that leads them properly to the third roll couple 24—24'.

The lower member of the third roll couple provides the appropriate rib 24^a and 75 channel 24^b, with as narrow lateral margins as is consistent with requisite strength, while the upper roll 24 provides wing-deflecting portions 24^c straddling exteriorly the wings of the strip to bend them inward, 80 so that they curve snugly around the sides of the rails 60^a, thus giving the interior curvature to both the head beads and producing the configuration shown at 44, Fig. 4. This intermediate step, of in-bending 85 both wings to almost meet constitutes part of the second and third steps and eases the subsequent action of the succeeding rolls in reentrantly bending the two wings, successively, to complete the strip. It will be 90 noted that where this inward deflection of both wings occurs, the core rails are united by the bridge 60^b, so that the lateral pressures are equalized. The leading guide 57 following the third roll-couple is preferably 95 provided with a wing guiding extension 57^a extending upwardly and forwardly over the core-rail 60^a to press the left wing of the strip inward somewhat, properly feeding it to the contiguous roll couple 25—25' by 100 which it is to be reentrantly bent. The bridge 60^b across the former rails 60^a preferably extends forward to substantially the forward end of said extension 57^a to give lateral strength to the rail at that point. 105

The upper roll 25, provides a narrow rib 25^c and a head forming channel 25^d, to bend reentrantly, to substantially completed condition, one lateral head of the strip, leaving the other strip-wing unaffected and producing the cross section 45 and completing the second major step. The succeeding leading guide 58 has an extension 58^a similar to the extension 57^a, to direct the right wing of the strip to the action of the next upper 110 roll 26. Said roll is provided with a narrow rib 26^c flanked by a head forming groove 26^d for the right hand head and a clearance groove 26^e for the previously formed left hand head. This roll-couple 115 forms the remaining head as shown by cross-section 46, and completes the third major step. The terminal rolls 27 and 27' are finishing rolls, sharply defined, as to their ribs 27^a, 27^b and grooves 27^b, 27^c and 120 usually operated under considerable pressure in coöperation with a slightly attenuated terminal portion of the rails 60^a, so as to cause a final compression and metal flow for the ultimate sharp definition of the 125 130

bends of the channel and heads and final compression of the border portions upon the central bar of the strip securing the ultimate cross-section 47. The confronting 5 channel engaging ribs 27^a and 27^c of the lower and upper rolls are preferably scored or knurled to increase the positiveness of the engagement of the rolls with the strip, and to work the bar-portions of the muntin 10 into intimate contact.

It will be observed that the formation of the strip by the reëntrant deflection first of one wing and then of the other enables the strip to be rolled with its edge portions 15 abutting closely so as to form a double bar at the base of the channel (although one layer of the bar is axially divided). In some forms of construction this closeness or meeting is not essential, but in many instances it is particularly desirable, for 20 strength and for uniformity of seating surface at the bases of the channels. Beyond the terminal rolls the strip passes through a guide 70 which may be of any desired 25 length, only a fragment being herein shown. As the guide is closed at the top and bottom, it directs the strip straight away from the roll without any bending thereof, and in practice the rolled muntin strips so produced 30 are satisfactorily straight, and free from curves or twists.

While I have herein described in some detail a particular apparatus for the practice of my invention, particularly constructed 35 with a view to working on zinc, and therefore performing its operations in a number of steps adequate to prevent possibility of damage to this rather weak metal, it will be apparent to those skilled in the art that 40 many modifications in the machine might be made without departure from the spirit of my invention and within the scope of the appended claims. Also it will be understood by those skilled in the art that by changes 45 in details of roll design specifically different configurations of strips might be produced within the spirit of my invention. It will be understood, therefore, that while I have herein described in detail a machine 50 which I have commercially used and found to be practical and efficient, for purposes of full disclosure of my invention, I do not limit myself in detail to the specific features of construction or specific operations of the 55 rolls in the method of rolling, further than as set forth in the claims.

Having described my invention, what I claim is:—

1. The art of rolling muntin strips in the 60 form of a double channel bar with hollow heads, which consists in rolling a flat strip into a central channel, flanked by half-heads with wings extending back past the bottom bar of the channel; reëntrantly rolling one 65 wing to complete a head and to lay the wing

border on the said bottom bar; and thereafter reëntrantly rolling the other wing in like fashion.

2. The method of rolling double channel strips having hollow heads flanking an intermediate bar, which consists in rolling a flat strip into a form presenting a central bar and flanking half-heads, having wings extending back past the bar; reëntrantly rolling the two wings successively each to 75 complete a head and lay its wing-border flat on said bottom bar with the wing-margins confronting and closely contiguous.

3. The method of rolling double channel strips which consists in rolling a flat strip 80 into a form presenting a central bar and flanking half-heads having wings extending back past the bar, mutually in-bending said wings nearly to contacting position, and successively reëntrantly rolling one wing to 85 complete a head and lay the wing border on said bottom bar, and reëntrantly rolling the other wing in like fashion.

4. The method of rolling double channel strips which consists in rolling a flat strip 90 into a form presenting a central bar and flanking half-heads having wings extending back past the bar, and thereafter mutually in-bending said wings nearly to contacting position, and successively reëntrantly rolling 95 one wing to complete a head and lay the wing border on said bottom bar, and reëntrantly rolling the other wing in like fashion while guiding the strip interiorly on a forming-core.

5. A machine for rolling muntin strips in the form of a double channel bar with hollow heads, comprising in combination successive roll couples including certain rolls adapted and arranged to bend the strip into 100 a central channel flanked by half-heads having wings extending back past the bottom bar of the channel; other succeeding rolls, adapted and arranged reëntrantly to roll one wing to complete a head and lay the 105 wing border on said bottom bar, and other succeeding rolls adapted and arranged reëntrantly to roll the other wing in like fashion.

6. A machine of the character described 115 comprising in combination successive roll couples, whereof the first are adapted to roll a flat strip into a central channel flanked by half-heads with wings extending back past the bottom bar of the channel, and others are successively adapted reëntrantly to roll one wing to complete a head and thereafter reëntrantly to roll the other wing in like fashion; and leading guides engaging 120 the first formed channel interposed between 125 the successive roll couples.

7. In a machine of the character described, the combination of roll couples comprising rolls adapted to shape a strip into a channel and succeeding rolls adapted to 130

work on the wing portions of the strip to complete the formation thereof, leading guides interposed between the several pairs of rolls below the path of material travel 5 through the roll and each arranged for engagement with the first-formed channel of the strip, said guides pivotally mounted for depression of the receiving end and limited in movement at that end by contact with the 10 contiguous roll.

8. In a machine of the character described, the combination of roll couples, comprising shaping portions leaving therebetween a material path, and a leading guide 15 interposed between two roll couples below the material path, said guide being movably mounted for depression of its receiving end below the level of the material path, and normally standing with its guiding crest 20 substantially in alignment with the bottom of the material path.

9. In a machine of the character described the combination of two roll couples, shaped to provide a material path, extending horizontally 25 through the machine, and a leading guide interposed between said roll couples, pivotally mounted between its ends, normally positioned with its guiding crest substantially on the line of the bottom of 30 the material path to the rolls, and tiltable for depression of its receiving end below the level of the material path to a position for substantial contact with the periphery of the lower roll of the first of said roll couples.

35 10. In a machine of the character described, the combination of a series of roll couples, comprising rolls adapted and arranged to operate upon a strip and form therein a central channel flanked by half-heads with wings extending back past the bottom bar of the channel, other succeeding 40 rolls adapted and arranged convergently to bend said wing members inwardly beyond the vertical, and other succeeding rolls 45 adapted reentrantly to bend said wing members to complete the head formation.

11. In a machine of the character described, the combination of a series of roll couples comprising rolls adapted and arranged to operate upon a strip and form therein a central channel flanked by half-heads with wings extending back past the bottom bar of the channel, other succeeding 50 rolls adapted and arranged convergently to bend said wing members inwardly beyond the vertical, a former interposed between the last said rolls, and other succeeding rolls 55 adapted reentrantly to bend said wing members successively to complete the head formation.

60 12. In a machine of the character described, the combination of a plurality of roll couples arranged successively to operate upon a strip of metal, the acting surfaces 65 of said roll couples being shaped to form

the strip into a hollow headed bar, with hollow heads in both sides; leading guides between the lower rolls of the successive couples, and a forming core spanning a plurality of said roll couples and passing 70 through the material-path defined by the acting surfaces of said roll couples and by the leading guide, said core comprising two parallel rails supported at their receiving ends, and at their forward or leading ends 75 positioned only by the rolls.

13. In a machine of the character described, the combination with first-operation rolls adapted and arranged to form a strip into a channel, half-heads and wings; successive second and third operation rolls adapted and arranged successively to bend reentrantly the side-wings to complete the formation of a double channel, and a core member, spanning the second- and third-operation rolls and supported at its receiving end. 80

14. In a machine of the character described, the combination with first-operation rolls adapted and arranged to form a strip 90 into a channel, half heads and wings; successive second and third operation rolls adapted and arranged successively to bend reentrantly the side wings to complete the formation of the double channel; leading 95 guides extending between contiguous rolls for engagement with the channel of the strip formed by the first operation rolls; and a core member spanning the second and third operation rolls and coöperating therewith 100 and with the leading guides, said core member supported at its receiving end and bifurcated throughout its length of coöperation with the second and third operation rolls. 105

15. In a machine of the character described, the combination with first-operation rolls adapted and arranged to form a strip into a channel, flanked by half heads and wings; wing-inbending rolls adapted 110 and arranged to bend said wings toward each other closer than the width of the strip through the half heads, other succeeding rolls adapted and arranged reentrantly to bend the side wings to complete the formation of a double channel, and the core member, spanning said rolls subsequent to the first-operation rolls, supported at its receiving end and providing rails corresponding with the interior shape of the half head and separated throughout their portions coöperating with said reentrantly bending roll, and having a bridge portion spanning said rail where said core member coöperates with 115 said inbending rolls. 120

16. In a machine of the character described, the combination with first-operation rolls, adapted and arranged to form a strip into a channel, flanked by half heads and wings, of successive second and third 130

operation rolls adapted and arranged successively to bend reentrantly the side wings to complete the formation of a double channel, leading guides between the lower rolls of the successive couples, and wing guiding extensions on the leading guides that direct the strips to the second and third operation rolls.

In testimony whereof I hereunto set my hand in the presence of two subscribing witnesses.

SILAS R. VANNAMAN.

In the presence of—

MARY F. ALLEN,
GEO. T. MAX, Jr.
